DISH RACK

Murray L. Atlas, Teaneck, N. J.

Application September 2, 1936, Serial No. 99,140
Renewed October 6, 1938

1 Claim. (Cl. 211—41)

This invention relates to improvements in dish-racks and more particularly has reference to and is illustrated in the accompanying drawings in its application to an article of the class described especially adapted for use in restaurants, hotels, steamships and institutions.

Referring to said drawings, I have illustrated in Fig. 1 in perspective, a suitable form of dish-rack embodying an application of my invention. Fig. 2 is a similar view of the outer frame. Fig. 3 a similar view of part of the interior rack thereof, and Fig. 4 a similar view of a modified form of rack.

Referring now more particularly to Fig. 2, it will be observed that the outer frame comprises preferably a base angle 5 and corner angles 6, supporting an upper rectangular flat frame member 7, connected to the base angle by straps 9, said parts being suitably welded or soldered as may be found convenient.

The lower rack shown in Fig. 1 comprises inner side rails 10, preferably of wood having cross bars 11, the same being seated upon the lower flange of the base angle frame 5, and thereupon rests another pair of preferably wooden side rails 12 having bars 13 at right angles to the bars 11, and another pair of side rails 15 are connected by bars 14, the side rails 12 resting upon the ends of the side rails 10 while the side rails 15 are preferably spaced upwardly from the side rails 12, the side rails 12 and 15 being preferably secured to the outer metal frame as indicated at 12', 15' thus providing a strong and sanitary form of dish-rack of simple construction, easily assembled, cleaned or repaired.

In the form shown in Fig. 3 the cut away por-

tions 16, 17 for clearing the uprights 9, 6 are shown more clearly and the upper and lower rack 15, 10 are secured together by dowels 18 allowing the same to be removed together and to rest upon the lower rack 10, in which case the 5 fastening means 12', 15' may be eliminated.

In the modification shown in Fig. 4 a wire basket is shown of suitable and conventional form to take the place of the wooden racks shown in Figs. 1 and 3 within the outer frame shown in 10 Figs. 1 and 2, but no claim is made for this wire form of basket.

Of course it will be understood that various modifications may be made in the construction and arrangement of parts without departing from 15 the spirit of the invention as claimed.

I claim:

A dish rack comprising an outer frame of appreciable height having upper and lower interconnected supporting bars and being entirely open 20 at the top and bottom, a pair of superimposed frames within said outer frame and removably supported adjacent the bottom of said outer frame on said lower supporting bar, cross bars on the lower of said pair of inner frames disposed 25 at right angles to bars disposed on the upper of said pair of inner frames, an upper frame disposed in said outer frame adjacent the upper end thereof and removably supported on the upper of said outer supporting bars in spaced relation 30 to said pair of superimposed lower frames, said upper frame being provided with bars which parallel some of the bars of said superimposed pair of frames.
